ELECTRIC SWITCH

Carl A. Schaefer, Detroit, Mich., assignor to
 Square D Company, Detroit, Mich., a corpora-
 tion of Michigan

Application November 21, 1936, Serial No. 112,089

9 Claims. (Cl. 200—83)

This invention relates to electric switches and more particularly to electric switches automatically operable in response to changes in an external condition.

5 One object of the present invention is to provide an improved means for manually opening the circuit through an automatic switch.

Another object of the invention is to provide an automatic electric switch having an overload relay with improved means for preventing disabling of said relay while current flows through the switch.

15 Another object of the invention is to provide an electric switch automatically operable in response to an external condition and having an overload relay with auxiliary contacts openable upon resetting of the relay to break the circuit through the switch.

20 Other objects and features of the invention will be readily apparent to those skilled in the art from the following specification and the appended drawings illustrating certain preferred embodiments of the invention in which:

25 Figure 1 is a front elevational view of the device according to the present invention.

Figure 2 is an enlarged view similar to Figure 1 with the cover removed and parts broken away to show internal parts.

30 Figure 3 is a horizontal sectional view on the line III—III of Figure 2.

Figure 4 is a detailed vertical sectional view on the line IV—IV of Figure 3.

Figure 5 is a view similar to Figure 4 with the parts in another position.

35 Figure 6 is a detailed sectional view on the line VI—VI of Figure 4.

Figure 7 is a vertical sectional view on spaced planes, the upper portion being a central longitudinal section and the lower portion thereof being a longitudinal section in a plane displaced toward the front of the switch.

40 The switch according to the present invention constitutes an improvement upon and a variation in that disclosed in applicant's co-pending application No. 77,723 filed May 4, 1936 for Electric switches and comprises an insulating enclosure 1 having a front cover 2 carrying a manual operator 3 pivotally mounted thereon. Upon a stationary bracket 4 within the enclosure are 45 pivotally mounted, as at 20, a pair of contact arms 5 and 6 having limited relative movement, with the arm 6 formed of conducting material and carrying a movable contact 7, and with the arm 5 formed of magnetic material and cooperating 50 with a permanent magnet 8 to effect quick make

and break action of the switch arms. A stationary contact 9 is mounted on a flexible arm 11 which bears against a cam member 12 rotatable to vary the position of the stationary contact 9 and hence the differential of operation of the 5 switch. A light tension spring 10 is connected to the arm 6 and biases the contact arms toward engaged position. The arm 5 is provided adjacent its lower portion with a pin 13 engageable by an insulating portion 14 rigid with a pivoted lever 15 10 to move the arms to disengaged position. The arm 5 has a limited movement relative to the arm 6 between the adjacent surface of the arm 6 and the back surface of the contact 7. In the closed position the force exerted upon the arm 5 15 by the magnet 8 increases the pressure between the contacts 7 and 9 by the bearing of arm 5 against the contact 7. As the insulating portion 14 engages the pin 13 in its downward movement it will effect initial movement of the arm 20 5 without moving the arm 6 which is maintained in place through the tension spring 10 until it is engaged by the arm 5. The force necessary to move the arm 5 against the attraction of the magnet 6 decreases rapidly with the air gap between the arm and the magnet so that the arm 5 will tend to move rapidly after the initial overcoming of the magnetic force at the closest position of the arm. Hence it will engage the arm 6 25 while moving and will effect relatively quick break of the movable contact 7 from the stationary contact 9. Similarly, upon closing, as the insulating portion 14 moves upwardly the arms 5 and 6 will move toward closed position under the bias of the spring 10. As the arm 5 approaches the pole faces of the magnet 8 the magnetic force exerted thereon increases rapidly 30 and effects the final closing movement of the movable contact 7 rapidly. Hence quick make and quick break operation of the movable contact 7 is attained. The rotation of the cam 12 35 which varies the position of the stationary contact 9 will serve to vary the air gap between the pole faces of the magnet 8 and the magnetic arm 5 since the position of the arm 5 is determined by 40 its engagement with the back face of the movable contact 7. This variation in air gap varies the initial force necessary to move the arm 5 toward disengaged position and hence varies the differential of operation of the switch. For moving the lever 15 there is provided a pressure responsive unit comprising a bellows chamber 16 45 having a bellows 17 disposed therein and connected to an operating pin 18 which bears at its upper end against the under side of the lever 15. 50 55

A compression spring 19 adjustable by means of a nut 21 may be provided to vary the limits of the range of operation of the device. Opposing movement of the lever 15 by the pressure unit 5 is a compression spring 22 bearing against the upper surface of the lever 15 and engaged at its upper end by a cupped nut 23 threaded upon an adjusting screw 24 for varying the range or operation of the switch.

10 The arm 5 is provided with an extension 25 engageable by a striker 26 for moving the movable contact to its separated position in response to a current overload. The striker 26 is mounted on a sliding member 27 biased to striking position 15 by a spring 28. The back portion of the slide 27 is provided with a latch engageable with a ratchet wheel 29 to maintain the slide in retracted position. The ratchet wheel 29 is disposed on a shaft mounted within a solder pot cylinder 31 containing 20 a metal alloy melting at a definite predetermined temperature in response to the heating effect of a resistor coil 32 thereabout. All of these related parts are supported upon an insulating base 33 which is readily demountable from the 25 rest of the switching mechanism. Pivots mounted on the base 33 and extending therethrough is a shaft 34 keyed at its front end to cooperate with the manual operator 3 and having at the front face of the base a rigidly connected 30 plate portion 35 carrying a re-setting arm 36 engageable with the slide 27 and having pivotally connected thereto a spring guide 38 carrying a compression spring 39 adapted to be moved over center to provide snap operation of the manually 35 movable parts. At the back of the base 33 the shaft 34 is connected to an insulating member 41 having a projecting portion 42 carrying a conducting bridging contact member 43. Rigidly mounted closely adjacent to the stationary magnet 8 is an insulating plate 44 preferably of a high resisting arc material. Mounted on this plate are a pair of flexible contact arms 45 and 46 carrying contact surfaces adjacent to their free ends adapted to be bridged by the conducting portion 43 when in the closed circuit position. The contact arm 45 is mounted on a metallic bracket 47 having a spaced surface 48 adapted to be engaged by a conducting portion 49 embracing a portion of the base 33 and contacting an end of heater coil 32. The contact arm 50 46 is rigidly secured at one end to a conducting plate 51 which is in turn connected by means of a stud 52 to a supporting bracket 53 leading to the main stationary contact supporting arm 11. Between the supported ends of the contact arms 55 45 and 46 is preferably disposed an insulating block 54 having an arc splitting tip 55 as shown. Rigid with the portion 42 there is provided an insulated portion 56 disposable between the contact portions of the arms 45 and 46 as the circuit is broken and cooperating with the tip 55 in suppressing any arc drawn between the cooperating contact surfaces. Upon the base 33 is mounted a contact terminal 57 connected by 60 means of plate 58 to one end of the heater coil 32 and on the bracket 4 is mounted a second terminal 59. The bracket 4 is connected to switch arm 6 by means of a flexible lead 61.

The electrical circuit through the switch is 70 from terminal 57 through plate 58, heater coil 32, conducting member 49, bracket 47, contact arm 45, bridging contact 43, contact arm 46, plate 51, bracket 53, contact arm 11, stationary contact 9, movable contact 7, contact arm 6, flexible lead 75 61, bracket 4, and terminal 59.

The operation of the switch will now be described: In the normal operation of the switch the pressure within the bellows chamber 16 will cause the lever 15 to move upwardly and downwardly depending upon the direction of the 5 change and the position of the switch. With the contacts in closed circuit position a decrease in pressure within the bellows chamber 16 will cause the lever 15 to move downwardly until the end moves the contacts to the disengaged position. Should the pressure within the bellows chamber thereafter increase the lever 15 will be moved upwardly, thus moving the insulating portion 14 out of engagement with pin 13 and permitting the contact arms to be moved into engaged position 10 under the bias of the spring 10. Should it be desired to manually open the circuit through the switch the operator 3 is simply moved in a clockwise direction to the "off" position whereupon the bridging contact element 43 will be moved out 15 of engagement with the contact surfaces of the arms 45 and 46, thus interrupting the circuit through the switch at this point. Should an overload occur through the switch the metal alloy within the solder pot cylinder 31 will become 20 melted due to the heat generated by the coil 32 thus permitting the ratchet wheel 29 to turn. The slide 27 will then be moved toward the right under the bias of spring 28 and the striker 26 will engage extension 25 on the arm 5 and will 25 move the movable contact 7 to disengaged position. To reset the overload relay after an automatic operation the manual operator 3 is rotated to the off position whereupon the arm 36 engages slide 27 and moves it back into position 30 where it is again latched by the ratchet wheel 29 providing the solder metal has cooled sufficiently 35 to prevent rotation of the wheel. It can readily be seen that the bridging contact element 43 will have been moved to disengaged position during 40 this operation so that, while the overload relay is in inoperative position due to resetting, the circuit through the switch is broken at the auxiliary contacts and it is impossible to disable the overload relay in such a manner as to permit over- 45 load currents to pass through the switch without protection.

While certain preferred embodiments of the invention have been specifically disclosed, it is understood that the invention is not limited 50 thereto as many variations will be readily apparent to those skilled in the art and the invention is to be given its broadest possible interpretation within the terms of the following claims.

What is claimed is:

1. In an electric switch, separable contacts, normally operable means responsive to an exterior condition for separating said contacts, abnormal means responsive to current overload for separating said contacts, auxiliary contacts in 60 circuit with said switch, and means for opening said auxiliary contacts while resetting said abnormal means.
2. In an electric switch, stationary and movable contacts, mechanism responsive to an exterior 65 condition for moving said movable contact to engaged and disengaged positions, means responsive to current overload through the switch for moving said movable contact to disengaged position, auxiliary contacts in series circuit with said 70 first-mentioned contacts, means for resetting said current responsive means, and means for separating said auxiliary contacts when said resetting means is operated.
3. In an electric switch, stationary and mov- 75

able contacts, mechanism responsive to an exterior condition for normally moving said movable contact, means responsive to current overload through the switch for moving said movable contact to disengaged position, means for resetting said overload means, and means opening the circuit through the switch independently of the position of the movable contact when said resetting means is operated, to prevent passage of current through the switch while the overload means is disabled and permitting said movable contact to be moved to engaged position by said mechanism in response to the exterior condition.

15 4. In an electric switch, relatively movable contacts, mechanism responsive to an exterior condition for normally effecting such relative movement, means responsive to current overload for effecting separation of said contacts regardless 20 of said condition, manual means for resetting said current responsive means, auxiliary contacts in series circuit with said first mentioned contacts, and means effecting separation of said auxiliary contacts in response to movement of 25 said manual means to resetting position.

5. In an electric switch, a stationary contact, a movable contact cooperating therewith, means biasing said movable contact to engaged position, means responsive to an external condition for 30 moving said movable contact to disengaged position, means responsive to current overload for moving said movable contact to disengaged position regardless of said condition, manual means for resetting said current responsive means, auxiliary contacts in series circuit with said stationary and movable contacts, and means effecting separation of said auxiliary contacts in response to movement of said manual means to 35 resetting position.

40 6. In an electric switch, switching contacts, mechanism responsive to an external condition for operating said contacts, means responsive to current overload for effecting separation of said contacts, a pair of resilient contact arms

in series circuit with said switch, a movable contact adapted to bridge said arms to complete the circuit through the switch, and resetting means for said current responsive means connected to move said bridging contact to disengaged position when operated to resetting position.

5 7. In an electric switch, a pair of superposed, resilient contact arms carrying opposed contact surfaces adjacent to their free ends, a stationary insulating member between said arms adjacent to their fixed ends and having a wedge-shaped portion extending toward said contact surfaces, a bridging contact element movable between said contact surfaces, and means for moving said contact element to perform the switching operation.

10 8. In an electric switch, a pair of superposed contact arms carrying opposed contact surfaces adjacent to their free ends, a bridging contact element swingable in a plane at right angles to 15 said contact surfaces into a position between and in engagement with said contact surfaces, an insulating barrier connected to said contact element and movable therewith, said barrier being disposed between but out of engagement with 20 said contact surfaces when said contact element is in disengaged position, and means for oscillating said contact element to perform the switching 25 operation.

9. In an electric switch, a pair of superposed, 30 resilient contact arms carrying opposed contact surfaces adjacent to their free ends, insulating surfaces disposed on opposite sides of said arms, an insulating member between said arms adjacent to their fixed ends and having a wedge-shaped portion 35 extending toward said contact surfaces, a bridging contact element movable into and out of engagement with said contact surfaces to effect the switching operation and an insulating portion disposed between said arms 40 and movable with said bridging contact into a position between said contact surfaces.

CARL A. SCHAEFER.
